Primary Examiner — Jennifer Rivard*Assistant Examiner* — Melanie Pellegrini(74) *Attorney, Agent, or Firm* — Banner & Witcoff, Ltd.(57) **CLAIM**

The ornamental design for a translucent wristband, as shown and described.

DESCRIPTION

FIG. 1 is a perspective view of a translucent wristband showing our new design;

FIG. 2 is a left side view thereof;

FIG. 3 is a right side view thereof;

FIG. 4 is a bottom view thereof;

FIG. 5 is a top view thereof; and,

FIG. 6 is a front view thereof.

The uneven length broken lines immediately adjacent to the shaded area represent unclaimed boundaries of the design. The even length broken lines showing interior features of the wristband form no part of the claimed design. The uneven length broken lines showing the remainder of the wristband are for environmental purposes only and form no part of the claimed design.
